(57) **CLAIM**

The ornamental design for a stand alone videophone, as shown and described.

DESCRIPTION

FIG. 1 is a top front perspective view of a stand alone videophone showing our new design;
FIG. 2 is a top plan view thereof;
FIG. 3 is a front elevational view thereof;
FIG. 4 is a rear elevational thereof;
FIG. 5 is a bottom plan view thereof;
FIG. 6 is a right side elevational view thereof;
FIG. 7 is a left side elevational view thereof; and,
FIG. 8 is a top front perspective view thereof corresponding to FIG. 1 but with parts in different positions.

1 Claim, 4 Drawing Sheets

Matter enclosed in heavy brackets [ ] appears in the original patent, but forms no part of this reissue; matter printed in italics indicated the additions made by reissue.
